(57) CLAIM

The ornamental design for a cap assembly for a feeding bottle, as shown and described.

DESCRIPTION

FIG. 1 is a side view of a cap assembly for a feeding bottle showing our new design;

FIG. 2 is a perspective view from the top thereof;

FIG. 3 is a side view thereof;

FIG. 4 is a different side view thereof;

FIG. 5 is a different side view thereof;

FIG. 6 is a different side view thereof;

FIG. 7 is a top view thereof; and,

FIG. 8 is a bottom view thereof.

The broken lines illustrate portions of the drawings that form no part of the claimed design.

1 Claim, 8 Drawing Sheets
